(57) CLAIM

I claim the ornamental design for a handle attached to three knives, as shown and described.

DESCRIPTION

FIG. 1 is a top front perspective view showing the handle attached to three knives of an embodiment of the present invention, with the middle knife being longer than the outer knives and the outer knives being of equal length;

FIG. 2 is a bottom rear perspective view of the handle attached to three knives of FIG. 1; and,

FIG. 3 is a top view of the handle attached to three knives of FIGS. 1 and 2.
